Des. 195,607
Patented July 2, 1963

195,607

PHOTOGRAPHIC PLATE DEVELOPING AND PROCESSING UNIT

David Gordon Sharp, Chapel Hill, N.C., assignor to Ward
Laboratories, Durham, N.C., a corporation of North
Carolina

Filed Nov. 5, 1962, Ser. No. 72,378

Term of patent 14 years

(Cl. D61—1)

Fig. 1

Fig. 2

Fig. 3

FIG. 4

FIG. 5

FIG. 6

FIGURE 1 is a perspective view of a photographic plate developing and processing unit showing my new design.

FIGURE 2 is a right side elevation view thereof.

FIGURE 3 is a front elevation view thereof.

FIGURE 4 is a plan view thereof.

FIGURE 5 is a left side elevation view thereof.

FIGURE 6 is a rear elevation view thereof.

I claim:

The ornamental design for a photographic plate developing and processing unit, substantially as shown.
